(57) **CLAIM**

The ornamental design for an electrical connector, as shown and described.

DESCRIPTION

The present Article relates to a male connector of a pair of connectors and comprises signal contacts and power supply contacts, the power supply contacts forming plugs.

FIG. 1 is a front view of an electrical connector showing my new design;

FIG. 2 is a top plan view thereof;

FIG. 3 is a rear view thereof;

FIG. 4 is a right side view thereof; and,

FIG. 5 is a left side view thereof.

The broken lines throughout the drawing figures are included for the purpose of illustrating portions of the connector that form no part of the claimed design.
